UNITED STATES PATENT OFFICE.

LAMONT H. STROUD, OF SHERIDAN, WYOMING.

STATION-INDICATOR.

1,392,718.

Specification of Letters Patent.

Patented Oct. 4, 1921.

Application filed April 23, 1919. Serial No. 292,123.

To all whom it may concern:

Be it known that I, LAMONT H. STROUD, a citizen of the United States, residing at Sheridan, in the county of Sheridan and 5 State of Wyoming, have invented certain new and useful Improvements in Station-Indicators; and I do hereby declare the following to be a full, clear, and exact description of the invention, such as will enable 10 others skilled in the art to which it appertains to make and use the same.

My invention relates to improvements in station indicators adapted for use in cars,

An important object of this invention is 15 to provide novel means for automatically starting and stopping the indicator to display the proper station upon approaching the station.

A further object of the invention is to 20 provide an indicator having novel means for controlling the indicator cloth from one roll to another whereby all slack is prevented in the indicator cloth.

A further object of the invention is to 25 provide a novel actuating means for the conveyer.

A further object of the invention is to provide an indicator which is simple to install, automatic in its operation, and 30 highly reliable in use.

Other objects and advantages of this invention will be apparent during the course of the following description.

In the accompanying drawings forming 35 a part of this specification and in which like numerals are employed to designate like parts throughout the same.

Figure 1 is a fragmentary side elevation of an apparatus embodying my invention, 40 parts thereof being shown in section,

Fig. 2 is a horizontal section taken on line 2—2 of Fig. 1,

Fig. 3 is an enlarged horizontal section taken on line 3—3 of Fig. 1,

Fig. 4 is a horizontal section taken on line 4—4 of Fig. 1,

Fig. 5 is a front elevation of the indicator embodying my invention, parts thereof being broken away,

Fig. 6 is a vertical transverse section taken on line 6—6 of Fig. 5,

Fig. 7 is a vertical transverse section taken on line 7—7 of Fig. 5.

In the drawings, wherein for the purpose of illustration is shown the preferred embodiment of my invention, the numeral 10 generally indicates a car having a running gear 11. Wheels 12 are included in the running gear and are mounted on tracks 13. A housing 14 is carried by the running gear 11 and receives an actuator rod 15. The actuator rod 15 is movable vertically and is normally held in a downward position by a coil spring 16. A trip block 17 clearly shown in Fig. 1 is adapted to engage the actuator rod 15 for pushing the same upwardly. The trip block 17 has connection at its lower end with a bell crank 18. The bell crank 18 has connection with horizontal and vertical links 19 and 20 respectively. An operating lever 21 which may be arranged at any point with relation to the trip lock 17 is connected to the vertical links 20 by a suitable connecting element 22. The lever 21 is adapted for positioning the trip lock 17 in an operative or non-operative position.

The actuator rod 15 has connection with a bell crank 23 pivotally secured as at 24 within the housing 14. A vertically disposed arm 25 is provided with a laterally extending pin 26 connected to the bell crank 23 by a link 27. A shaft 28 is provided with an extensible slip joint 29. A universal joint 30 connects the shaft 28 to the vertical arm 25. A vertical shaft 31 is connected to the shaft 28 by a universal joint 32.

The upper end of the shaft 31 extends into an indicator casing 33. An electric motor 34 is arranged within the casing 33 and is provided with a pinion 35 meshing with a relatively large gear 36. The relatively large gear 36 is mounted on a transverse shaft 37 which also carries a pulley 38. The electric motor has connection with a suitable source of electrical energy 39 through wires 40.

As clearly shown in Figs. 1 and 4, a pulley 41 is carried by a frame 42 disposed within the casing and has connection with the pulley 38 by a belt 43. The belt 43 may be provided with a twist as indicated in dotted lines in Fig. 1 for reversing the direc-

tion of rotation of the pulley 41. Spools 44 and 45 are disposed within the casing and receive and dispense an indicator cloth 45'. The indicator cloth 45' is connected 5 at its ends to the spools 44 and 45 and passes over a pair of rollers 46 and 47. The rollers 46 and 47 are carried by the frames 42 and are disposed rearwardly of the sight opening 48. The roller 47 is provided with cog 10 wheels 49 engaging marginal apertures 50 in the indicator cloth 45'. The lower spool or roller 47 has connection with the pulley 41 and is adapted for positively driving the indicator cloth a predetermined portion of 15 its length at each operation of the electric motor regardless of the amount of cloth on either of the spools 44 and 45.

No rotate the spools 44 and 45 at speeds to insure the equal dispensing and receiving 20 of cloth, I have provided an equalizer 51. The equalizer 51 includes a pair of spools 52 which have rigid connection with the spools 44 and 45. An equalizer tape 53 is adapted to be wound about the spools 52 25 as is the cloth 45' wound about the rollers 44 and 45. An equalizer belt 54 of an elastic material is disposed about the spool 52 and the equalizing tape 53 whereby the spools 44 and 45 are caused to rotate in syncro- 30 nism.

As clearly illustrated in Figs. 1 and 3, a pair of contacts 55 and 56 are interposed in one of the wires of the electric circuit. The contact 56 has rigid connection with a brake 35 57 adapted to engage the equalizer 51 for stopping the operation of the indicator cloth upon the completion of one rotation of the operating gear 36. The integral elements 56 and 57 are pivotally supported by the bracket 58 as indicated at 58'. A master releasing and locking arm 59 is pivotally secured at its rear end to the gear 36 as indicated at 60. A coil spring 61 which is carried by a bracket 64 tends to normally retain 40 the master arm 59 parallel to the gear 36 and in engagement with the contact 56 whereby the same is normally spaced from the contact 55. The upper end of the shaft 31 is provided with an offset 65 engaging the 45 master arm 59 when the same is in a horizontal position. Upon the rotation of the shaft 31 in the direction of the arrow in Fig. 1 the master arm 59 is thrown out of engagement with the contact 56 thereby closing the circuit and starting the motor. The gear 36 is caused to partake of a complete 50 revolution and carries with it the master arm 59 which upon completing the revolution again engages the contact 56 and breaks the circuit. Upon the disengagement of the master arm with the contact 56, the brake 55 60 65 is brought out of engagement with the equalizer and the movable contact into en-

gagement with the stationary contact by a coil spring 66. One complete revolution of 65 the gear 36 causes the name of the next station to appear on the indicator cloth.

If desired, a bell 67 may be connected to the contacts 55 and 56 by wires 68. A suitable source of electrical energy 69 may be 70 employed for the bell 67. In the use of my invention, it will be apparent that the trip rod 15 is caused to move upwardly by engagement with the trip block 17, with the result that the shaft 31 is caused to rotate 75 in the direction indicated by the arrow and thereby cause the master arm 59 to be released from engagement with the contact 56.

As described, the contact 56 engages the contact 55 upon being released and thereby 80 closes the circuit which causes the motor 34 to operate. The operation of the motor 34 rotates the pulley 41 which positively rotates the indicator cloth the necessary distance to present the name of the next station. The equalizer 51 serves to rotate the spools 44 and 45 to transfer the indicator cloth 45' from one to the other without any slack.

While I have shown and described the preferred embodiment of my invention, it is understood that I may make such minor changes in arrangement and construction of parts, as will remain within the spirit of the invention and the scope of the appended 95 claims.

Having thus described my invention, what I claim is:-

1. An indicator including, a pair of spools, an indicator cloth wound about said spools, 100 an electric motor, a gear having connection with said motor, a pair of contacts, a source of electrical energy having connection with said motor and said contacts, a control arm pivotally carried by said gear and extending 105 radially from the center of the same, said control arm normally engaging one of said contacts, spring means for retaining said control arm in engagement with one of said contacts, and an operating rod adapted for 110 disengaging said control arm from one of said contacts whereby a circuit may be completed to said electrical energy and said motor for rotating said gear and operating said indicator cloth.

2. An indicator including, an indicator cloth, spools supporting said indicator cloth, an electric motor, a source of energy for said electrical motor, conductors connecting said electrical energy of said motor, contacts interposed in said conductors, one of said conductors being pivotally supported, a brake arm having connection with said pivoted conductor and adapted for locking said indicator cloth against rotation, a gear having 120 connection with said motor, a radially dis-

posed control rod pivotally carried by said gear and adapted for engaging said pivoted contact, means to disengage said control bar from said pivoted contact whereby said contacts may engage and complete the circuit between said motor and said electrical energy, said gear upon the completion of a revolution being adapted to engage said

control arm with said pivoted contact whereby the circuit is opened. 10

In testimony whereof I affix my signature in presence of two witnesses.

LAMONT H. STROUD.
